UNITED STATES PATENT OFFICE

HOWARD R. VAN KIRK, OF LARCHMONT, NEW YORK, ASSIGNOR TO GENERAL PERMANENT WAVE CORPORATION, OF NEW YORK, N. Y., A CORPORATION OF NEW YORK

STEAM HAIR WAVING APPLIANCE

Application filed February 11, 1931. Serial No. 515,004.

My invention comprises certain improvements in the construction, form and arrangement of the various parts of a steam hair waving appliance whereby the condensate, except that retained by the wound tress, may be entirely removed by suction which forms a vacuum in the heater which encloses the wound tress; whereby the condensation of the steam is materially retarded; whereby a steam tight closure at the scalp end of the heater may be ensured; and whereby the wound tress may be spaced from the inner walls of the heater tube to permit the circulation of steam around the tress.

A practical embodiment of my invention is represented in the accompanying drawings in which:

Fig. 1 represents the appliance in side elevation in its operative position;
Fig. 2 represents an inner end view of the appliance;

Fig. 3 represents a longitudinal vertical section through the appliance;

Fig. 4 represents a transverse section taken in the plane of the line IV—IV of Fig. 3, looking in the direction of the arrows; and

Fig. 5 represents a transverse section taken in the plane of the line V—V of Fig. 3, looking in the direction of the arrows.

The hair waving appliance comprises, generally, the steam heater and the mandrel enclosed thereby, on which mandrel the tress of hair to be waved is wound and secured. The inner and outer tubes of the heater are denoted by 1 and 2 respectively. The inner tube is preferably made of metal. The outer tube is preferably made of fiber or other heat insulating material and it is spaced from the inner tube to produce an air space between the tubes for serving the double purpose of keeping down the temperature of the outer tube so that the appliance can be readily handled when in operation, and also for materially delaying the condensation of the steam in the inner tube. The outer tube is provided with means as an eye 3 for the attachment of a weighted suspension cord 4 as is usual, the appliance being so suspended that its inner or scalp end will be somewhat below its outer end.

A suitable closure is provided for the outer end of the heater, which closure in the present instance comprises the closed end 5 of the inner tube and the cap 6 for the outer tube. A steam inlet nipple 7 and a suction outlet nipple 8, both of which pass through the parts 5 and 6 serve to cause the end cap to space the outer end of the outer tube from the outer end of the inner tube. 55

The end closure for the inner or scalp end of the heater is shown as a flexible tube 9, for instance a rubber tube and a hand clamp carried by the inner end of the outer tube for temporarily closing the flexible tube around the tress with a steam tight joint. This flexible tube is shown as stretched over the slightly enlarged inner end of the inner tube and tightly wedged between it and the walls of the enlarged bore at the inner end of the outer tube to form a steam tight joint between 60 the inner tube and the flexible tube. 70

The hand clamp which I have shown for temporarily closing the flexible tube around the tress comprises a ferrule 10 surrounding the inner end of the outer tube from which ferrule an arm 11 projects, said arm having lateral branches 12 and 13 with uprising ends 14, 15. To the end 15 I hinge a clamp plate 16, U-shaped in cross section, and to the end 14 I hinge a cam lever 17 arranged in position when closed to force the clamp plate 16 toward the lateral branches 12 and 13 to squeeze the walls of the flexible tube 9 together, around the tress adjacent the scalp. 75

The suction outlet nipple 8 is provided within the inner tube of the heater with a small extension tube 18 which leads along the bottom of the inner tube to the lower inner end of the heater into a proper position for removing the condensate from within the 80 heater when suction is applied thereto, to form a partial vacuum in the heater.

The mandrel 19 on which the tress of hair is wound and secured in the usual manner is provided at its outer end with a fluted handle 85 20 which loosely fits the bore of the inner tube to center the wound tress and thus space it from the walls of the bore of the inner tube. The grooves 21 through the fluted handle 20 serve to permit the steam to pass by the han- 100

dle from the steam inlet nozzle 7 into intimate contact with the wound tress on the mandrel. The small extension suction tube 18 passes through one of the grooves 21 in the handle and acts as a guide in the insertion and removal of the mandrel to and from the heater.

The inlet nozzle 7 is provided with a suitable flexible tube 22 which leads from a source 10 of steam supply, not shown herein. The suction outlet tube 8 is similarly provided with a flexible tube 23 which leads to a suction means, not shown herein, for forming a vacuum in the heater to ensure the removal of the condensate therefrom either during or after the steaming operation or during both the steaming operation and after the steaming operation is completed. The source of steam 15 supply and the suction means, which are not shown herein, are fully illustrated and described in my copending application filed of even date herewith, its Serial No. being 515,003.

From the above description it will be seen 25 that I have provided a steam hair waving appliance which, because of the spaced outer tube of heat insulating material, may be readily handled during or immediately after the steaming operation. It will furthermore 30 be seen that by providing the spaced inner and outer tubes a dead air space is formed which materially delays the condensation of the steam within the heater. Furthermore, it will be seen that I have provided a very 35 simple and steam tight closure for the inner or scalp end of the heater. It will be seen also that the extension tube 18 is positioned to take care of the condensate which may gather at the lower inner end of the heater. Also, 40 the provision of the enlarged handle at the outer end of the mandrel serves to permit this handle to space the wound tress from the walls of the bore of the inner tube of the heater, thus allowing the steam to have ready 45 access to the entire wound tress.

It is evident that various changes may be resorted to in the construction, form and arrangement of the several parts without departing from the spirit and scope of my invention, and hence I do not intend to be limited to the particular embodiment herein shown and described, but

What I claim is:—

1. In a steam hair waving appliance, a wound tress heater having a steam inlet and a suction outlet.
2. In a steam hair waving appliance, a wound tress heater having a steam inlet at its outer end and a suction outlet passage 60 leading from the inner end of the heater.
3. In a steam hair waving appliance, a wound tress heater having a steam inlet at its outer end and a suction outlet tube leading from the inner end of the heater at its bottom outwardly through its outer end.

4. In a steam hair waving appliance, a wound tress heater having steam inlet and suction outlet passages through its outer end, said suction outlet passage having an extension leading to the inner end of the heater.

5. In a steam hair waving appliance, a wound tress heater having a steam inlet and a suction outlet, said heater comprising an inner tube and an outer tube surrounding and spaced from the inner tube.

6. In a steam hair waving appliance, a wound tress heater having a steam inlet and a suction outlet, said heater comprising an inner tube and an outer tube of insulating material surrounding and spaced from the inner tube.

7. In a steam hair waving appliance, a wound tress heater having a steam inlet and a suction outlet and also having a flexible closure for its inner end comprising a compressible tube and means for closing the tube around the tress.

8. In a steam hair waving appliance, a wound tress heater having a steam inlet and a suction outlet and also having a flexible closure for its inner end comprising a compressible tube and means carried by the heater for closing the tube around the tress.

9. In a steam hair waving appliance, a wound tress heater having a steam inlet and a suction outlet, said heater also having a rigid closure for its outer end and a flexible closure for its inner end.

10. In a steam hair waving appliance, a wound tress heater having a steam inlet and a suction outlet, said heater also having a rigid closure for its outer end and a flexible closure for its inner end, said flexible closure comprising a compressible tube and means for closing the tube around the tress.

11. In a steam hair waving appliance, a wound tress heater having a steam inlet and a suction outlet, said heater also having a rigid closure for its outer end and a flexible closure for its inner end, said flexible closure comprising a compressible tube and means carried by the heater for closing the tube around the tress.

12. In a steam hair waving appliance, a wound tress heater having a steam inlet and a suction outlet, said heater comprising inner and outer spaced tubes, a rigid closure for spacing the outer ends of the tubes apart and a flexible inner closure for spacing the inner ends of the tubes apart.

13. In a steam hair waving appliance, a wound tress heater having a steam inlet and a suction outlet, said heater comprising inner and outer spaced tubes, a rigid closure for spacing the outer ends of the tubes apart and a flexible inner closure for spacing the inner ends of the tubes apart and a clamp carried by the outer tube for compressing the inner closure around the tress.

14. In a steam hair waving appliance, a mandrel on which the tress is wound and a

heater therefor having a steam inlet and a suction outlet, said heater comprising inner and outer spaced tubes, end closures therefor and releasable means for forming a steam tight joint between the tress and the inner end closure.

suction outlet, said heater comprising inner and outer spaced tubes and closures for the inner and outer ends of said tubes, the inner closure comprising a flexible tube wedged between the walls of the inner and outer tubes to form a steam tight joint. 70

In testimony, that I claim the foregoing as my invention, I have signed my name this 15th day of January, 1931.

HOWARD R. VAN KIRK. 75

15. In a steam hair waving appliance, a mandrel on which the tress is wound and a heater therefor having a steam inlet and a suction outlet, said heater comprising inner and outer spaced tubes, end closures therefor and releasable means for forming a steam tight joint between the tress and the inner end closure, said mandrel having a handle at its 15 outer end loosely fitting the bore of the inner tube of the heater to center the tress within the tube.

16. In a steam hair waving appliance, a mandrel on which the tress is wound and a heater therefor having a steam inlet and a suction outlet, said heater comprising inner and outer spaced tubes, end closures therefor and releasable means for forming a steam tight joint between the tress and the inner end closure, said mandrel having a fluted handle at its outer end loosely fitting the bore of the inner tube of the heater to center the tress within the tube.

17. In a steam hair waving appliance, a mandrel on which the tress is wound and a heater therefor having a steam inlet and a suction outlet, said heater comprising inner and outer spaced tubes, end closures therefor and releasable means for forming a steam tight joint between the tress and the inner end closure, said mandrel being provided with a head at its outer end loosely fitting the bore of the inner tube to center the tress therein, said head having openings therethrough for the passage of steam thereby.

18. In a steam hair waving appliance, a mandrel on which the tress is wound and a heater therefor comprising a tube having a steam inlet and a suction outlet, end closures for the heater and releasable means for forming a steam tight joint between the tress and the inner end closure, said mandrel having a handle at its outer end loosely fitting the bore of the heater tube to center the tress within the tube.

19. In a steam hair waving appliance, a mandrel on which the tress is wound and a heater therefor comprising a tube having a steam inlet and a suction outlet, end closures for the heater and releasable means for forming a steam tight joint between the tress and the inner end closure, said mandrel having a handle at its outer end loosely fitting the bore of the heater tube to center the tress within the tube, said heater having openings therethrough for the passage of steam thereby.

20. In a steam hair waving appliance, a wound tress heater having a steam inlet and a
